ABSTRACT: An electrostatic deflector consisting of a central plate and a pair of outer plates spaced from and parallel to each other. Each plate is provided with a slot for line of sight passage through the deflector and the central plate is charged at a high constant voltage with respect to the outer plate.

ELECTROSTATIC DEFLECTOR FOR SELECTIVELY AND ADJUSTABLY BENDING A CHARGED PARTICLE BEAM

BACKGROUND OF THE INVENTION

Beams of low-energy ions can be reflected by electrostatic mirrors or deflectors which make it possible to use multiple ion sources with accelerators, mass spectrometers, and elsewhere more efficiently and with greater convenience. Deflectors of this type are superior to magnetic deflectors for certain applications because for heavier ions increasingly massive magnetic structures are required whereas no such increase in mass for the electrostatic deflector takes place. The electrostatic device is also capable of fast switching as very little energy is stored, and furthermore such a device is able to deflect ions of different masses of the same energy without separating them.

One of the principle drawbacks and limiting factors involved in the use of electrostatic deflectors is that such devices usually employ a screen or grid through which the beam passes to effect its deflection. The presence of the grid tends to attenuate the beam and its presence in the electric field has a tendency to produce small lenslike regions which defocus the beam by acting on separate portions of the beam. In addition, the grid eventually burns out as a result of sputtering and produces secondary emissions of electrons when struck by the ion beam.

SUMMARY OF THE INVENTION

The invention described herein was made in the course of, or under a contract with the U.S. Atomic Energy Commission.

The present invention overcomes or reduces the disadvantages and drawbacks of presently used electrostatic deflectors by avoiding the use of a screen through which the beam passes. In accordance with this invention, three spaced electrodes are arranged with aligned slots, the central electrode being charged at a different voltage than the outside electrodes. In a typical application of this device, the electrodes are mounted at a 45° angle with respect to the path of the ion beam which passes through the slots without contacting any of the electrodes. When it is desired to bend the ion beam, the voltages are applied to the electrodes as described and the beam is deflected.

It is thus a principal object of this invention to provide an electrostatic deflector of greater efficiency and improved emittance characteristics.

Other objects and advantages of this invention will become readily apparent from the following description of a preferred embodiment of this invention taken with reference to the accompanying drawing.

BRIEF DESCRIPTION OF THE DRAWING

FIG. 1 shows schematically a typical application of this invention;

FIG. 2 shows an isometric view, in partial section, of a preferred embodiment of this invention.

DESCRIPTION OF THE PREFERRED EMBODIMENT

Referring to FIG. 1 there is illustrated a mass spectrometer M arranged to receive an ion beam from either of ion sources S1 and S2. The former is located with respect to spectrometer M in such a way that its ion beam will pass directly into spectrometer M. The latter is located at a position offset from the entrance to spectrometer M, as shown. Electrostatic deflector 10 made in accordance with this invention, is placed in line with both the entrance to spectrometer M and the beam produced by source S2. When only source S1 is generating a beam, the beam from source S1 will pass through deflector 10 without any interference or attenuation, as will be seen later. When S1 is not generating and S2 is producing a beam, deflector 10 is energized and the beam from S2 is reflected into spectrometer M. While this deflection, angle A, is a right angle

in the illustration, it is understood that other angles are possible.

For the details of deflector 10, reference is made to FIG. 2 where it is seen that it consists of electrodes which are spaced 5 flat plates 12, 14 and 16 parallel to each other. Plates 12, 14, and 16 which are made from electrically conductive material are provided with elongated slots 18, 22 and 24, respectively, whose length is not of any great significance except that they should be long enough to accommodate the bend in the beam without touching or being unduly influenced by the edges of any of the electrodes and to pass a beam through when not energized without interference. The width of slots 18, 22, and 24 must be large enough to accommodate in a similar fashion to the size of the beam to be accommodated.

Center plate 14 is placed at some DC voltage with respect to outer plates 12 and 16 from a DC power supply E, the polarity of course being the same as the charge on the ions to be deflected. While outer plates 12 and 16 are shown as being 20 grounded (i.e. same potential), the relative voltages may be varied without departing from the principles of this invention, depending on the characteristics to be imparted to deflector 10. It is seen that the spacing of each of plates 12 and 16, respectively, from central plate 14, as well as the potential differences existing from central plate 14 to outer plates 12 and 16, respectively, determine the magnitudes and the gradients 25 of the electric fields existing in the separating spaces. Thus, if deflector 10 is symmetrical both geometrically and electrically, and the charge on the plates is insufficient to deflect beam away as shown in FIG. 2, a beam of properly charged ions passing through deflector 10 will not be bent in its direction, but will be offset laterally, somewhat similar to the effect a glass plate has on a beam of light striking it at an angle, due to differences in the index of refraction.

In the event that the intensity of the electric fields is sufficient to prevent the beam from passing through deflector 10, the angle of reflection C is always equal to the angle of incidence B, shown in FIG. 1.

An electrostatic deflector incorporating the principles of this invention has been found useful to bend both positive and negative ion beams, including H- and H+ ions, and heavier ions including those of oxygen. One of the particular advantages of this invention when used in bending beams of 40 heavier ions is that the deflector itself does not have to be increased in mass as is the case when magnetic devices are utilized. In addition, because the deflector does not store significant amounts of energy, it can be switched on and off with far greater rapidity than a magnetic deflector is capable of 45 because of the expanding and collapsing magnetic field phenomenon.

Another important advantage of the inventive arrangement arises from the fact that the deflector tends to focus the beam in a plane without defocusing in a transverse plane. Thus more 50 than one of these devices can be utilized to control independently the focal properties of beams.

It is thus seen that there has been provided an improved electrostatic device of which while only a preferred embodiment of the invention has been described, it being understood that many variations thereof are possible without departing from the principles of this invention as defined in the appended claims.

I claim:

- 60 1. An electrostatic deflector for a beam of charged particles comprising:
  - a. means placed in line with said beam comprising three mounted electrodes of electrically conducting material spaced from each other;
  - b. said electrodes each having formed therein an opening, the openings being aligned for unobstructed passage of said beam, said openings being elongated slots of sufficient lengths to accommodate bending of said beam at a right angle without interference by said electrodes; and
  - c. means for

1. maintaining the center electrode at a greater absolute constant voltage potential than the outer electrodes at a polarity to repel said charged particles, the outer electrodes being at the same potential;
2. varying said potential to correspondingly vary the angle at which said beam is deflected; and

3. selectively connecting and disconnecting said potential applied to said center electrode to selectively deflect said beam or permit the unobstructed passage of said beam through said openings.
